super and their various operating features as may be required. The invention may be used in connection with a variety of different types of machinery and apparatus, and is not limited to any particular type of apparatus. It is, however, particularly adapted for use in connection with a core drilling rig of the type shown in Fig. 1, and is particularly adapted for use in connection with a core drilling rig of the type shown in Fig. 2.

UNITED STATES PATENT OFFICE

2,614,420

LOAD INDICATING DEVICE

Frank Miller, Orange, N. J., assignor to Ingersoll-Rand Company, New York, N. Y., a corporation of New Jersey

Application May 28, 1949, Serial No. 95,939

2 Claims. (Cl. 73—143)

1

This invention relates to load indicating devices and more particularly to load indicating devices for drill hoists.

One object of this invention is to indicate the torque on the drum of a drill hoist.

Another object of the invention is to control the rotation of the hoist drum.

Other objects will be evident from a study of the following specification.

In the drawings, in which similar reference numerals refer to similar parts,

Fig. 1 is a side elevation showing a core drilling rig provided with the invention.

Fig. 2 is a side elevation, partly in section and enlarged, showing the drill hoist and the load indicating device.

Fig. 3 is a sectional view of the bearing assembly taken on the lines 3—3 of Fig. 2.

In the practice of boring holes through rock formations, a cutter 10 is rotated by connected drill rod sections 11 driven by a machine 12 at the top of the bore hole 13. This is called core drilling. For purposes of illustration a typical core drilling rig of the shot bit type is shown in Fig. 1 in which the cutter 10 is composed of a core barrel 14 and a bit 15. Around the periphery of the bit 15 are diagonally located slots 16 containing steel shot 17. A derrick structure 19 over the hole 13 supports the drilling assembly which is raised and lowered by means of a wire rope 20. The rope 20 is secured to a hoist 21 which receives and winds the rope 20 on a drum 22.

The abrasive action of the shot against the rock 18 does the cutting and because of this the weight, or load, on the bit must not be too great. If the load on the drill is too great, the bit will not bore a straight hole. It is the intention of the applicant to provide a load indicating device that will allow the hoist operator to know the load on the drill at all times thereby preventing any overload on the cutter. A preferred form of the invention is shown in detail in Fig. 2.

A hoist 21 having a drum 22 to receive the rope 20 and to hold the rope in tension is shown in the drawing. The drum 22 is provided with a brake 23 consisting of a brake band 24 which extends around the periphery of the drum 22 and which is secured to a brake lever 25 having opposed threads 26. By moving the lever 25 in one direction, the band 24 is tightened about the drum 22. If the brake lever 25 is moved in the opposite direction, the band 24 is loosened about the drum.

For the purpose of transmitting the torque on

the drum 22 to a load indicating device, a worm gear 27 is provided around the periphery of the drum 22. A shaft 28, with its axis perpendicular to the axis of the drum 22, is provided with a worm 29 engaging the worm gear 27 on the drum 22 and converting the rotary motion of the drum 22 to linear motion of the shaft. One end of the shaft 28 terminates in a ratchet wheel 30. A hand lever 31, with a selective pawl 32 to enable the shaft 28 to ratchet in either direction, fits around the ratchet wheel 30 and allows the shaft 28 to control the rotation of the drum 22 when the brake 23 on the drum is released.

A measuring device 33 for measuring the torque on the drum 22 is provided on the end of the shaft 28 opposite the ratchet wheel 30. This device comprises a casing 34 having a cylindrical bore 35 into which the shaft 28 extends and is provided with a piston 36 attached to the end of the shaft 28. Fluid is adapted to fill that portion 37 of the cylinder 35 which lies between the piston 36 and the shaft end of the cylinder 38 and is introduced through a port 39. A pressure gauge 40 is attached to the casing 34 and indicates the fluid pressure.

While drilling the worm 29 on the shaft 28 is arranged to engage the worm gear 27 only when the cutter 10 is rotating. When pulling drill 10 from or returning it to the hole 13, the worm 29 is arranged to be disconnected from the gear 27 and to this end the shaft 28 and cylinder casing 34 are pivotally supported on a bracket 44. The casing 34 comprises a cylinder barrel 41 bolted to an end plate 42 which is pivotally connected to a vertical member 43 of the derrick structure 19 by means of a bracket 44.

At its other end the shaft 28 is journaled on a post 45 having a bearing assembly 46 to receive the shaft 28. The upper bearing half 47 is hinged to the lower half 48 in order that the shaft 28 may be inserted between them. When the shaft is in the bearing the worm 29 engages the worm gear 27. A hinged bolt 49 with a hand nut 50 fastens the bearing together. The top of the upper bearing 47 has a semi-circular depression 51 to receive the shaft 28 when disengaged from the worm gear 27.

During the operation of this device the drill assembly is lowered into the hole. When the cutter 10 is at the bottom of the hole 13 the shaft 28 is placed in the bearing assembly 46 which is then locked together by means of the hand nut 50. The brake 23 on the drum 22 is then released throwing all of the load on the

worm gear 27 and worm 29 thence to the fluid in the cylinder 35 through the piston 36. The torque on the drum is indicated by the fluid pressure shown on the pressure gauge 40. The operator rotates the worm 29 by the hand lever 31 until the proper weight for the best drilling results is on the cutter 10. As long as the drill is in operation, the operator can maintain the proper pressure by referring to the pressure gauge 40 and by controlling the rotation of the drum 22 with the hand lever 31.

While a specific form of the invention has been shown and described, it is to be understood that various changes and modifications may be made without departing from the spirit of the invention as set forth in the appended claims.

I claim:

1. In a load indicating device for drill hoists, a drum to receive a rope and to hold the rope in tension, a worm gear around the periphery of the drum, a shaft having a worm to engage the worm gear to control the rotation of the drum, a piston on one end of the shaft, a cylinder having fluid therein enclosing the piston said cylinder having one of its ends pivoted to allow the worm on the piston shaft to be disengaged from the worm gear on the drum, and a measuring device for indicating the pressure on the fluid.
2. In a load indicating device for drum hoists, 30

a drum to receive a rope and to hold the rope in tension, a worm gear around the periphery of the drum, a shaft having a worm to engage the worm gear and to control the rotation of the drum, a piston on one end of the shaft, a cylinder enclosing the piston and having fluid therein, said cylinder having one of its ends pivoted to allow the worm on the piston shaft to be disengaged from the worm gear on the drum, a pressure gauge communicating with the cylinder in order to indicate the pressure of the fluid in the cylinder, a clamp for holding the shaft against rotation in order to lock the drum, and manually operated means for effecting rotation of the shaft in order to adjust the load on the drum.

FRANK MILLER.
